TOOL FOR SEVERING THE FLANGES OF CHANNELS

Thomas M. Porter, Brookline, Mass., assignor to
 H. K. Porter, Inc., Somerville, Mass., a corporation of Massachusetts

Application November 21, 1950, Serial No. 196,798

3 Claims. (Cl. 30—226)

This invention relates to a tool for severing the flanges of channels. The object is to provide an efficient hand tool whereby the two flanges of a channel may be severed simultaneously by shear cuts along lines directly opposite one another.

One application of such a tool is in connection with metal channels used in laying carpets. The edge of the carpet is inserted in the channel and the channel suitably anchored to floor or wall to hold the carpet in position. The channels must be cut to suit the particular job. By means of the tool about to be described the two flanges may be cut along opposite lines and thereafter the web of the channel may be bent, broken or cut as desired.

My invention will be well understood by reference to the following description taken in connection with the accompanying drawings, wherein:

Fig. 1 is an elevation of a tool illustrative of the invention with the jaws closed;

Fig. 2 is a partial edge view thereof, as seen from the right of Fig. 1;

Fig. 3 is an elevation of the head levers as seen from the opposite side from Fig. 1, with the jaws in open position;

Fig. 4 is a fragmentary side view showing the tool applied to a channel in position to effect a cut; and

Fig. 5 is an edge view showing the head of the tool applied to a channel (which appears partially broken away), this figure illustrating how a slanting cut is made.

My invention is herein shown as embodied in a tool of the multiple lever type embodying the principles disclosed in the patent to Lindsay 146,829, January 27, 1874, whereby in the present instance adequate power is obtained in a relatively small tool actuated by one hand. The tool shown comprises two head levers 10-r and 10-l which are substantially, although not literally, mirror images of each other, but otherwise duplicates. The letters l and r are expressive of "left" and "right" when viewing Fig. 1. In the description I shall sometimes use the numeral alone when what is being said applies to both levers. They have hub-like portions which overlap and receive the pivot pin 12 pivoting the two head levers together, and when so pivoted the distal ends of the levers provide cooperating jaws, hereinafter to be described in detail, and the proximal ends are tails providing for the application of force thereto as by means of the handles 14-l and 14-r pivoted to the jaw lever

tails on the pins 16, and themselves having short arms pivoted together at 18. Herein the head levers 10 are of the uncrossed type and closing movement of the jaws occurs when the lever tails (pivot pins 16) are pressed apart, this however being effected by an approximation of the handles 14, resulting from a closing movement of the gripping hand. The points 16 are directly opposite each other. Herein the head lever 10-r is flat, whereas the head lever 10-l is offset, so that its hub portion which receives the pivot 12 and the distal jaw portions of the two head levers 10—10 may move over one another in the manner of shear blades.

The jaw portions of the head levers 10, have each a leading edge 20-l and 20-r respectively, which may extend substantially radially of the pivot 12 and, rearwardly thereof a slot, which defines an edge 22-l and 22-r respectively, parallel to the first edge, the slots when the tool is open as seen in Fig. 3 providing two open ended parallel throats at opposite sides of the leading edges of the jaws respectively, and corresponding to the respective slots. Into these throats the flanges of the channel C may be inserted as shown in Fig. 4. When the jaws swing to the closed position of Fig. 1 the leading edge of each lever moves in shearing relation past the edge provided by the rear wall of the slot on the other lever. Thus, referring to Fig. 3, the lever 10-r swings clockwise and the lever 10-l counterclockwise, and the edge 20-r moves across the throat in lever 10-l to cooperate with edge 22-l and the edge 20-l will move across the lefthand throat, viewing the figure, to cooperate with edge 22-r. In this movement the two flanges of the channel are severed.

It will be apparent from comparison of the Figs. 1 and 2, that the various edges here shown are now bevelled, but are substantially straight across. While it would be possible to bevel at least some of these edges, it is desirable that certain at least should be flat and of substantial width to provide gaging surfaces on which a flange of the channel may rest as is illustrated by the upper flange of the channel C in Fig. 4, to so position the channel that the cuts will both be in one plane perpendicular to the flanges.

The ends of the jaws are bevelled off as illustrated at 26 and best seen in Figs. 2 and 5. This permits the tool to be applied at an angle to the channel as shown in Fig. 5, the bevel at one side of the tool or the other, as the case may be, resting against the web of the channel with the cutting edges extending diagonally of the flanges.

This permits a slanting cut to be made when it is desired to form a mitered end on the channel. Clearly a triangular piece may be cut out in this way and the web of the channel bent without parting it to form a corner, or a series of such pieces may be cut out to permit bending the channel to a curve.

In the example of the invention shown a spring 28 is provided between the handles, normally tending to press the handles apart and open the jaws of the tool. A suitable latch 32 is provided which in the present embodiment of the invention serves to hold the jaws closed when the tool is not in use and also limits the opening movement. For this purpose the latch, which is pivoted on one of the pivot pins 16, is provided with an angular slot receiving the end of the other. When the pin 16-r is in the vertical part 34 of the slot, as shown in Fig. 1, the jaws are held closed. When the latch is swung clockwise the jaws move open, the pin moving in the generally horizontal portion 36 of the slot as illustrated in Fig. 4, the opening movement however being limited when the pin reaches the end of the slot. The arrangement is such that the jaws are then in the position shown in Fig. 4 and Fig. 3, with the two throats unobstructed and ready to receive the flanges of the channel.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be

had to the appended claims to indicate those principles of the invention exemplified by the particular embodiment described and which I desire to secure by Letters Patent.

I claim:

1. A tool for severing the flanges of channels comprising a pair of interpivoted head levers having tails providing for the application of force thereto and mutually overlapping distal jaws, each jaw having a leading edge and, rearwardly thereof a slot, the rear wall of which defines an edge parallel to the first edge, the slots when the tool is open providing two open-ended throats at opposite sides of the leading edges of the jaws respectively and corresponding to the respective slots, in which throats the flanges of the channel are received to be severed by a movement of the jaws wherein the leading edge of each lever moves in shearing relation past the edge provided by the rear wall of the slot in the other lever.

2. A tool as defined in claim 1 wherein the distal portions of the jaws are bevelled rearwardly and outwardly from their meeting plane to permit their application to the web of the channel with the edges extending diagonally to the flanges to cut the latter across on a slant.

3. A tool as defined in claim 1 wherein at least certain of the jaw faces defining the throats are wide and define a right angle with the adjacent cutting edges to provide gaging surfaces to so position the channel that the cuts will both be in one plane perpendicular to the flanges.

THOMAS M. PORTER.
